UNITED STATES PATENT OFFICE.

EDWARD B. JACOBSON, OF PITTSFIELD, MASSACHUSETTS, ASSIGNOR TO J AND B MANUFACTURING COMPANY, OF PITTSFIELD, MASSACHUSETTS, A CORPORATION OF MASSACHUSETTS.

IGNITION-TIMER.

1,379,821.

Specification of Letters Patent. Patented May 31, 1921.

Application filed November 8, 1918. Serial No. 261,607.

To all whom it may concern:

Be it known that I, EDWARD B. JACOBSON, a citizen of the United States, residing at Pittsfield, in the county of Berkshire and State of Massachusetts, have invented 5 certain new and useful Improvements in Ignition-Timers, of which the following is a specification.

The present invention particularly concerns improvements in the rotor portion of my prior invention as shown and described in U. S. Letters Patent No. 1,188,451, in ignition timers, dated June 27, 1916, and has for its object to further improve the construction of the contact roll and its mounting whereby the wearing properties of these parts are greatly improved and the timing apparatus as a whole is rendered more durable and efficient.

With the foregoing and other objects in view, the present invention consists in the construction, combination and arrangement of parts, as hereinafter more particularly described and pointed out in the claims.

Referring to the accompanying drawings,—Figure 1 is a central vertical section of an ignition timer embodying my present invention and operatively mounted upon a shaft; Fig. 2, a face view of the same, the front portion of the housing being cut away; Fig. 3, a side elevation of the housing, housing clamp and clamp support, assembled in operative relation, the rear portion of the housing being cut away; Fig. 4, a side elevation of the rotor carrier; Fig. 5, a front elevation of the same; Fig. 6, a longitudinal vertical section showing the method of mounting the rotor carrier on the shaft, the front and rear portions of the rotor assembly being cut away; Fig. 7, a sectional bottom view of the contact-arm on a longitudinal curved line; Fig. 8, a longitudinal vertical section of the rotor portion operatively mounted, as shown in Fig. 1; Fig. 9, a vertical

45 cross-section of the rotor assembly on a plane coincident with the inner face of the outer radial carrier-arm 20; Fig. 10, a side elevation of the rotor assembly, Figs. 9 and 10 indicating in dotted lines the limit of 50 inward swing of the contact-arm; Fig. 11,

a side elevation of one of the plates of the contact arm; Fig. 12, a similar view of a modification; Fig. 13, a side elevation of a modification of the contact-roll axial support; and Fig. 14, an end view of the same. 55

The mechanism herein illustrated is designed for use in connection with a four-cylinder explosive engine having a gear-driven cam-shaft operated by the main engine shaft, but it should be understood, 60 however, that my invention is applicable for use with motors having any number of explosion cylinders, and may be otherwise mounted and driven.

My present invention may be adapted to 65 any suitable form of housing or casing, the form of casing 1 herein illustrated being adjustably mounted on the front end of the engine housing 2 and arranged to inclose a shaft 3, which is preferably geared to the 70 main engine shaft (not shown) and extends through a suitable opening in the wall of the engine housing.

The rear end of the casing 1 is open and seated in a circular recess 4 provided in the 75 face of the engine housing 2, the wall of said recess being adapted to prevent eccentric displacement of the casing. Forward displacement of the casing 1 is prevented by a spring clamp 5 removably secured at its rear end to a stud or bolt 6 fixed to the wall of the engine housing 2, and engaging at its opposite end the front of the casing 1, which is tapered inward and has a central depression to receive a boss 7 provided on the clamp 5. Axial movement of the casing 1 for regulating the time of ignition is controlled by a lateral arm 8 externally mounted on the casing and provided with a bushing 9 to receive a control-rod 80 (not shown).

Within the casing 1 is an insulation ring 10 provided at regular intervals with arcuate contacts 11, 11, which are embedded on its inner rim and suitably connected to separate terminals 12, 12, etc. arranged on the outside of the casing 1, for connection with the primary circuit of separate induction coils. 95

Mounted to rotate with the shaft 3 within 10

the casing 1 is a metal carrier 13 in the form of a sleeve which is normally secured against axial movement on the shaft by a transversely arranged removable pin 14 5 projecting through the shaft and extending at opposite ends into slots 15, 15, provided on the outer rim of the carrier. The pin 14 is secured against end-wise displacement by a shouldered washer 16 fitted over the 10 outer end of the carrier and extending over the ends of the pin 14, the reduced outer end of the shaft 3, which projects through the washer 16, being threaded to receive a pair of nuts 17, 18, which are employed in conjunction with a flat washer 19, engaging the washer 16, to secure the latter in position.

The carrier 13 is laterally provided with a pair of fixed arms 20, 20, arranged in parallel in spaced relation to each other and 20 pivotally supporting at their outer ends a contact-arm comprising preferably a pair of oppositely arranged plates 21, 21, secured at their rear ends to the carrier arms 20, 20, by a transversely arranged pin 22. 25 Said pin 22 has reduced extensions 23, 23, at opposite ends adapted to fit into suitable openings 24 in the plates 21, 21, projecting slightly beyond the same and burred at their extremities to prevent lateral displacement 30 of the plates. As shown, the relative position of the plates 21, 21, is maintained by a transverse spacer-pin 25 which is preferably arranged at a middle point on the plates and secured thereto in a manner similar 35 to the pin 22, transverse openings 26 adapted to receive the reduced extremities 27 of the spacer-pin being provided in the plates.

Supported in the jaw formed by the outer 40 ends of the plates 21, 21, is a brush or contact-roll 28 loosely mounted upon a hardened steel bushing 29 carried on a stationary axle pin 30 similar to the contact-arm supporting pin 22 and spacer-pin 25 and secured 45 preferably in a similar manner, to the plates 21, 21, which are provided with suitable transverse openings 31 to receive the reduced extremities 32, 32, of the axle pin which are burred over the plates and secure 50 the bushing 29 firmly in a stationary position.

In my prior invention, as shown and described in the patent above referred to, the contact-roll was mounted directly upon the 55 axle pin which was constructed of less durable material than the contact-roll and without an intervening element such as the present hardened bushing 29. This construction resulted in undue wear of the pin, causing 60 oscillation of the contact-roll and irregularities in the circuit connections.

While I deem the provision of a separate intermediate member of hardened metal, such as the bushing 29, best adapted to pre-

vent rapid and uneven wear of the axial 65 support for the contact-roll, I have shown in Figs. 12, 13, and 14 a modified form of embodiment of my invention, wherein the contact-roll axle pin 33 is diametrically enlarged between the side plates 34 to provide 70 a suitable substitute for the bushing 29, involving a unitary structure of hardened metal having a reduced extension 35 at each end adapted to fit into suitable slots 36 provided in the outer ends of the side plates 75 and having corresponding flat faces to prevent rotation of the pin.

The free end of the contact-arm is normally impelled outward into movable engagement with the insulation ring 10 and 80 contacts 11 under the impulse of a torsion spring 37 carried on the contact-arm supporting pin 22 between the arms 20, 20, one end of the spring being extended forward to bear preferably against the underside of 85 the spacer-pin 25 while the opposite end of the spring is extended downward for engagement with the carrier 13, thereby fixing the reflex and expansion limits of the spring torsion. The outward swing of the contact- 90 arm assembly is limited positively, preferably by means of shoulders 38, 38, provided on the outer side of the carrier arms 20, 20, near their bases, and forming stops for engagement by the plates 21, 21, at a predetermined point in the arc of swing of the contact-arm, (see Fig. 10) the lower rim of the plates being preferably extended downward at their rear ends to form a 95 foot 39, 39.

The general operation of the present invention, taken in connection with the description contained in the specification of my said prior invention, will be readily understood.

What I claim as new, and desire to secure by Letters-Patent, is:

1. In a device of the class described, a support, a contact-member mounted thereon and movable relatively thereto, and a hardened metallic bearing member rigidly mounted on said support and interposed between said support and the contact-member and adapted to maintain the axis of said contact-member in constant parallel relation to said support.

2. An ignition timer having a rotor mounted to rotate and having a jaw, a roller mounted in and arranged to travel with said jaw, and a unitary roller journal comprising a single hardened journal bearing member and means independent of the bearing member to retain the latter in stationary position in said jaw and to support the roller.

3. An ignition timer having a rotor mounted to rotate and having apertured jaw members 21, a roller 28 mounted on and arranged to travel with said jaw members,

and a roller journal comprising a pin 30 extending at opposite ends into and secured in fixed relation to said jaw members and a bushing 29 mounted in stationary position 5 on the pin and forming a hardened engaging bearing medium for the support of the roller.

In testimony whereof I hereunto affix my signature in the presence of two witnesses.

EDWARD B. JACOBSON.
